US00D462662S

(12) **United States Design Patent** (10) Patent No.: **US D462,662 S**
(45) Date of Patent: **** Sep. 10, 2002**

(54) **SENSOR CONNECTOR**

(75) Inventor: **Eric Lindekugel**, Fort Collins, CO (US)

(73) Assignee: **Datex-Ohmeda, Inc.**, Madison, WI (US)

(**) Term: **14 Years**

(21) Appl. No.: **29/136,010**

(22) Filed: **Jan. 23, 2001**

(51) **LOC (7) Cl. 13-03**

(52) **U.S. Cl. D13/146; D24/169**

(58) **Field of Search** D13/146; D24/169; 439/599, 589, 374, 909; 600/322, 323

(57) **CLAIM**

The ornamental design for a sensor connector, as shown and described.

DESCRIPTION

FIG. 1 is an isometric view of the front of the connector;

FIG. 2 is an isometric view of the back of the connector;

FIG. 3 is a front view of the connector;

FIG. 4 is a back view of the connector;

FIG. 5 is a view of the left side of the connector;

FIG. 6 is a view of the right side of the connector;

FIG. 7 is a top view of the connector; and,

FIG. 8 is a bottom view of the connector.
